GRANULATION OF NONGRANULAR MATERIALS

George E. Cox, Niagara Falls, N. Y., and Walter G. McBurney, Niagara Falls, Canada, assignors to American Cyanamid Company, New York, N. Y., a corporation of Maine

Application May 14, 1937, Serial No. 142,632

1 Claim. (Cl. 23—239)

The present invention relates to a method of treating non-granular materials to produce therefrom substantially spherical or globular aggregates in the form of substantially stable hard

5 granules.

In many arts today, materials heretofore in the form of powders or powdery materials, the individual particles of which are either of uniform or of heterogeneous sizes, are more desirable for 10 many purposes in the form of granules. For instance, fertilizer materials such as calcium cyanamid, heretofore marketed as a powdery or non-granular product, becomes more desirable and acceptable to the trade in the form of granules with 15 minimum quantities of fines and many thousands of tons of this material are now marketed annually. This is but one example of granular materials which are constantly finding a larger place in industry.

20 The principal object of the invention is, therefore, to produce granules from non-granular materials by a simple and efficient method with minimum handling difficulties so that as a result of these operations, a maximum number of optimum sized aggregates are produced with minimum quantities of fines, and of a stable character.

To this end, the invention contemplates in its broadest aspect, passing the material to be granulated through or between closely approaching surfaces such as rolls or presses, so that the material will be compacted together in the form of a flake. It is intended that the thickness of this flake will, in large measure, determine the eventual diameter of the produced granule. The invention 35 contemplates subsequently treating the flake so as to break it up into smaller pieces, which will be termed herein as rough granules. These broken pieces will, of course, have relatively sharp edges and will be of irregular shape. The subsequent treatment includes tumbling these rough granules upon themselves to knock off the rough edges and bring them more nearly into a spherical or globular shape. During the tumbling operation, the fines or final particles produced as a 40 result will be in large measure pounded into the granules and become a part thereof. If the material treated is of such a character that more fines are produced than can normally be pounded into and become incorporated with the granules, they may be subsequently separated.

The invention likewise contemplates the heat treatment of the thus rounded granules to reduce their liquid content to a desired point, such point being determined by the degree of hardness de-

sired dependent upon the use to which the granular material will be put.

The invention further consists in the further details hereinafter described.

In the drawings:

Fig. 1 illustrates diagrammatically the character of equipment used to carry out the process;

Fig. 2 showing the remaining equipment;

Fig. 3 is a sectional view along the line 3—3 of Fig. 2.

Referring now with particularity to the embodiment illustrated and taking crude calcium cyanamid as a representative material to be treated, although it is to be understood that this is illustrative only, the fully hydrated powdery cyanamid is introduced from a suitable source into hopper 1 from which it may be fed by screw device 2 into a suitable type of automatic weighing scale 3 emptying into mixer 4. In some instances, the cyanamid entering the mixer will contain sufficient moisture so that in the subsequent compacting or flake forming operation, sufficient adherence may be obtained between the particles. If, however, the cyanamid at the point of entering the mixer 4 does not contain sufficient moisture, additional quantities may be added from tank 5 through metering device 6 until the proper consistency has been obtained. Where desired, the water in the tank 5 may contain materials dissolved therein, such, for instance, as potash salts and/or phosphates where a complete fertilizer is desired. On the other hand, such liquid may contain binding materials such as a solution of calcium nitrate or the like. Again, it may contain such substances as the sugars where it is desired to utilize the dicyandiamid inhibiting effect thereof during the process. These, or any combinations of the above, may be utilized in any manner desired and they may be introduced from a single tank or an additional tank 7 with 20 its metering device 8 may be utilized.

The requisite amount of liquid, where necessary, and containing desired additional material, or none at all, having been introduced into the mixer 4 as at 9, the cyanamid and the added material are well mixed by means of the rotating paddles 10 inside of the mixer. From the mixer, the moist cyanamid then passes to a compacting nucleus or flake forming device, which may conveniently take the form of a squeeze roll mechanism shown generally at 11. These rolls are so arranged with relation to each other, that their proximity may be adjusted and the cyanamid in passing between them is compacted and formed into flakes. The clearance between the rolls is 30 35 40 45 50 55 60 65 70 75 80 85 90 95

so adjusted that a flake of any desired thickness may be obtained, which thickness will in large measure determine the eventual diameter of the finished granule.

5 From the flaking device 11, the flakes drop into a breaker mechanism 12 containing rotating knives 13 which, during the passage of the cyanamid through the breaker, cut or break the flakes into smaller fragments which may be 10 termed partially formed or rough granules. The action of the knives in the breaker is not such as to again reduce the flakes to powder but should be only carried to the extent that fragments or rough granules are formed. rolls to form flakes, the thickness of the flake largely determining the eventual diameter of the granules, breaking up the flakes into rough granules, tumbling the rough granules upon themselves to round up the same and compact the solid matter thereof while driving the liquid content thereof to the surface, separating the over-

size masses from the desirably sized granules by passing the result of the granulating operation over a screen, and thereafter separately drying the rounded compacted granules freed from oversize.
